(57) **CLAIM**

The ornamental design for a protective folio for multiple types of input devices, as shown and described.

DESCRIPTION

FIG. 1 is a perspective open view of our protective folio for multiple types of input devices showing our new design in an open configuration;

FIG. 2 is a top plan view thereof;

FIG. 3 is a bottom plan view thereof;

FIG. 4 is a front elevational view thereof;

FIG. 5 is a back elevational view thereof;

FIG. 6 is a left side elevational view thereof;

FIG. 7 is a right side elevational view thereof; and,

FIG. 8 is a perspective view showing our new design in a closed configuration.

The broken lines represent environment and form no part of the claim.

1 Claim, 8 Drawing Sheets
